(57) **CLAIM**

The ornamental design for a theft deterrent apparatus, as shown and described.

DESCRIPTION

FIG. 1 is a top plan view of a theft deterrent apparatus, in an engaged state, showing our new design;

FIG. 2 is a bottom plan view thereof;

FIG. 3 is a right side elevational view thereof;

FIG. 4 is a left side elevational view thereof;

FIG. 5 is a front end plan view thereof;

FIG. 6 is a rear end plan view thereof;

FIG. 7 is a top elevational view showing the design in a disengaged state;

FIG. 8 is an enlarged front elevational view of the pin element thereof;

FIG. 9 is a top perspective view showing the design in a partially engaged state; and,

FIG. 10 is a right side elevational view thereof.
